LEO F. ADT, OF ALBANY, NEW YORK.

EYEGLASS-MOUNTING.

1,173,912.

Specification of Letters Patent. Patented Feb. 29, 1916.

Application filed December 30, 1915. Serial No. 69,319.

To all whom it may concern:

Be it known that I, LEO F. ADT, of Albany, in the county of Albany and State of New York, have invented certain new and useful 5 Improvements in Eyeglass-Mountings; and I do hereby declare the following to be a full, clear, and exact description of the same, reference being had to the accompanying drawings, forming a part of this specification, and to the reference-numerals marked 10 thereon.

My present invention relates to eyeglasses and more particularly to eyeglasses of the finger-piece type in which two guard levers 15 disposed transversely of the bridge or support carry at their rear ends nose engaging pads or guards and at their forward ends are provided with finger grips which, when pinched together, spread the nose pads and 20 disengage them from the nose. The pads, through the medium of the levers, are normally pressed together to grip the nose by springs acting against the guard levers and reacting against the support and this invention 25 has to do with structures in which the springs are arranged upon supporting and centering projections and it is desired that they be rather freely removable and replaceable over the free ends of such projections.

The invention has for its object to provide, with due regard to considerations of manufacturing economy and convenience, a simple and convenient means for retaining 30 the springs upon their projections, which means will also act as the abutment for taking the thrust of the spring against the support. A particular construction of the spring also enters into the combination in 35 its mode of coöperation with its retaining 40 means.

To these and other ends the invention resides in certain improvements and combinations of parts all as will be hereinafter more fully described, the novel features being 45 pointed out in the claims at the end of the specification.

In the drawings: Figure 1 is a top plan view of one guard lever unit of a finger-piece eyeglass mounting constructed in accordance with and illustrating one embodiment of my invention, only fragments of the lens and bridge being shown and the parts being represented on an enlarged scale; Fig. 2 is a bottom plan view; Fig. 3 is an inner 55 side view looking toward the lens of one-half of the mounting, the bridge being broken

away; Fig. 4 is a bottom plan view showing the guard lever in position to release the nose bearing pad from the nose; Fig. 5 is a front view of the bridge end and support to 60 illustrate the pivot member and the spring centering projection, the spring and guard lever being removed, and Fig. 6 is a detail perspective view of the spring taken from below.

Similar reference numerals throughout the several figures indicate the same parts.

I have illustrated and will describe only one guard lever unit at one end of the bridge, it being well known that the same structure 70 is duplicated at the other end except for "rights" and "lefts" and the description will hence be in the singular. In this view, 1 indicates the usual rigid bridge and 2 and 3 the edge and face lens straps carried thereby 75 and by means of which the lens 4 is rigidly connected to the bridge. Intermediate the central or curved portion of the bridge and the straps is a substantially horizontal enlargement 5 forming a table on which the 80 guard lever and its attendant mechanism is carried. The guard lever indicated generally at 6, has a suitable finger-piece 7 at its forwardly projecting end and 8 indicates any desired form of nose pad carried by the 85 rear end of the lever. The pivot 9 of the lever may and does, in this instance, consist of a shouldered screw threaded into the support 5 and having an overhanging or enlarged head 10 between which and the support 90 the lever is confined to vibrate in a fixed horizontal plane.

Beneath the bridge table or support 5 and fixed thereto is a downwardly extending vertical post or projection 11 which is in 95 alinement with the pivot 9 and hence with the axis upon which the guard lever turns. The projection may be tubular as shown to receive the pivot screw or a part of it and at its lower or free extremity it has an overhanging rim portion or shallow shoulder 100 12 and at one side, preferably the side toward the bridge, there is built onto this shoulder a laterally projecting lug 13 that is flush with the end face of the centering 105 projection.

The actuating spring, shown in detail in Fig. 5, is preferably of the flat spiral type and composed of a flat ribbon of metal wound into a coil with the outer end 14 110 extending outwardly at a tangent to hook over a downwardly dipped portion 15 in

the rearward arm of the guard 11. The spring encircles the tube or projection 11 and on its inner extremity it is provided with a downward extension 16 parallel with the centering projection and lying closely against the same to engage the lug 13 close to its base. For this purpose the lug is preferably undercut as shown at 17 at the point of abutment.

10 The spring is separate and detachable and may be detached or applied independently of the guard lever. To attach it, the coils are engaged under the lug 13 at one side and then pressed down around the projection, the inner coils being expanded or spread slightly in the operation so that when in place, the end of the inner coil hugs the projection but without cramping the flexing movements of the spring as a whole. As the end 14 is engaged with the arm of the guard lever 6, the projection 16 automatically rotates into engagement with the side of the lug 13 and it will be noted that by positioning the lug as shown and described, it directly engages the outer arm or end of the spring which is the part of the latter most liable to be deflected from its true plane and holds it in position. To remove the spring, the described motions are reversed, that is, the outer arm is first disengaged from the guard lever and that side of the coil which is opposite the lug 13 is then first raised.

35 It will be noted that the shallow rim or shoulder 12 not only assists in holding the spring in place, but is a strengthening factor in the formation of the lug 13, the projection being, as stated, preferably tubular and very thin. It will be further noted that there are no abrupt bends in the spring at any point and no bends at all at the inner

end where a bend in the material is most liable to result in breakage. The projection 16 is symmetrically continuous with the curve of the inner convolution and need not be made by bending the inner extremity but is preferably formed integrally and rolled out along with the body of the ribbon.

45 I claim as my invention:

1. In a finger-piece eyeglass mounting, 50 the combination with a support and a guard lever pivoted to turn thereon, of a centering projection rigidly carried by one of said parts in alinement with the axis of the lever and provided with a lateral abutment at 55 its outer end and a coil spring surrounding the projection and adapted to be applied and removed over the end thereof and over the abutment, one end of the spring being provided with an axial extension interlocking with the abutment and the other being arranged to act against the other part.

2. In a finger-piece eyeglass mounting, 60 the combination with a support and a guard lever pivoted to turn on one side thereof, 65 of a centering projection fixed to the other side of the support in alinement with the axis of the lever and having at its outer or free end a lateral lug and a flat spiral spring surrounding the projection and adapted to be applied and removed over the free end thereof, the inner end of the spring being provided with a downward extension 70 parallel with the centering projection and lying against the same to engage the lug, 75 the outer end of the spring being arranged to act against the guard lever.

LEO F. ADT.
